US0D1101450S

(12) **United States Design Patent** (10) **Patent No.:** **US D1,101,450 S**
(45) **Date of Patent:** **** Nov. 11, 2025**

(54) **DUAL ATTACHMENT FASTENER**

(71) Applicant: **I AM THE OCEAN, LLC**, Coral Springs, FL (US)

(72) Inventor: **Siddhi Desai**, Parkland, FL (US)

(73) Assignee: **I AM THE OCEAN, LLC**, Coral Springs, FL (US)

(**) Term: **15 Years**

(21) Appl. No.: **29/890,675**

(22) Filed: **Apr. 26, 2023**

(51) LOC (15) Cl. **08-08**

(52) U.S. Cl.

USPC **D6/553**

(57) **CLAIM**

The ornamental design for a dual attachment fastener as shown and described.

DESCRIPTION

FIG. 1 is a front isometric view of a dual attachment fastener showing my new design;

FIG. 2 is a front elevation view thereof;

FIG. 3 is a right side elevation view thereof; and

FIG. 4 is a rear elevation view thereof;

FIG. 5 is a left side elevation view thereof;

FIG. 6 is a top plan view thereof;

FIG. 7 is a bottom plan view thereof; and,

FIG. 8 is an isometric view of the dual attachment fastener with an attached accessory.
The broken lines in FIG. 8 are for the purpose of illustrating environment and form no part of the claimed design.

1 Claim, 8 Drawing Sheets
